UNITED STATES PATENT OFFICE

2,663,455

CAN

Harry Sebell, Syracuse, N. Y., assignor to Reynolds Metals Company, Richmond, Va., a corporation of Delaware

Application April 27, 1951, Serial No. 223,400

1 Claim. (Cl. 220—27)

1

This invention relates to cans and especially to so-called paint cans which are commonly used for packaging ready-mixed paint.

The paint cans now in common use are made with a closure-receiving collar within the can body at its upper end, which collar is seamed to the top edge of the can body with a lock seam, and is provided with an opening that is closed by a closure or cover element of the friction plug type. To open a can of this type it is necessary to pry the friction plug type cover off from the collar.

One object of my present invention is to provide a novel closure for the collar in a can of the above type, which closure includes a closure member of soft material, preferably soft metal such as aluminum, which can be easily cut by a knife-like implement for the purpose of opening the can.

Another object of the invention is to provide a novel closure which includes a brush-wiping ring within the opening of the collar and on which a person may wipe his brush after dipping it into the paint in the can.

A further object of the invention is to provide a closure which presents a drain opening immediately outside of the wiping ring, through which opening surplus paint forced from the brush during the wiping operation may drain back into the can.

In the drawings, wherein I have illustrated a selected embodiment of my invention,

Fig. 1 is a vertical, fragmentary, sectional view showing the upper end of a can embodying one form of my invention;

Fig. 2 is a sectional view of the soft metal closure member;

Fig. 3 is a plan view of the retaining or clamping ring shown in Fig. 1 by which the soft metal closure member is retained in place;

Fig. 4 is an enlarged fragmentary section through one edge of the can illustrated in Fig. 1 to better illustrate the construction;

Fig. 5 is a sectional view similar to Fig. 1, but on a smaller scale, showing a different embodiment of the invention;

Fig. 6 is a plan view of the clamping or sealing ring shown in Fig. 3.

In Fig. 1 of the drawing, 1 indicates the can body and 2 is the closure-receiving collar, the peripheral edge of which is seamed to the top edge of the can body by a lock seam 3.

The collar 2 is of the type usually employed in paint cans now in common use and it is deformed to present the annular groove 4, the

2

inner wall 5 of which defines the closure-receiving opening 6. The upper edge of the annular wall 5 is bent or rolled over to provide the bead 7 as usual in paint cans.

In accordance with my invention the opening 6 in the collar is closed by a closure element which includes a closure member 8 of thin soft metal, or other appropriate material, which can be easily cut, and which spans the opening 6, 10 the edge of the member 8 underlying the bead 7. Said member 8 is formed with a peripheral depending skirt 9 which fits tightly against the wall 5 of the collar 2.

My improved closure also includes a clamping 15 or retaining ring 10 which fits within the skirt 9 and serves to clamp the latter tightly against the wall 5 of the collar.

The clamping ring 10 is made with an outer ring section 11 which engages the skirt 9 and 20 clamps it against the wall 5, and an inner ring section 12 which is spaced from the outer ring section 11, the bottom edges of the inner and outer ring sections 12 and 11 being rigidly connected at a plurality of points by bridge portions 13. The space 15 between the inner and 25 outer ring sections is open at the bottom except at the places where the bridge portions 13 are located. The upper edge of the inner ring section 12 is preferably rolled inwardly to form a bead 14.

30 The can is opened by cutting the member 8 along a line immediately inside of the bead 7, and since said member 8 is made of thin soft metal this cutting operation can be easily performed by any knife-like implement.

35 If the member 8 is cut entirely around the bead then the central portion thereof may be removed thereby opening the can, and when the can is opened the clamping means 10 presents 40 an annular brush-wiping ring situated within the opening 6, said brush-wiping ring being constituted by the beaded upper edge 14 of the inner ring section 12. The space 15 between the two ring sections 11 and 12 constitutes a drain 45 opening through which surplus paint that is forced from the brush during the wiping operation may drain back into the can.

In paint cans as now commonly used the brush 50 is wiped against the bead 7 of the vertical wall 5 and during this operation the surplus paint is very apt to flow over into the groove 4. With my improvements, however, the surplus paint forced from the brush as it is being wiped on the bead 14 will flow into the space 15 and thus 55 drain back into the can.

A closure embodying my invention is prevented from being forced outwardly from the wall 5 by the bead 7 which overlies the peripheral edge of the closure, and the clamping ring 10 is constructed to clamp the skirt 9 against the wall 5 with sufficient force to prevent the closure from being moved inwardly.

The brush-wiping section 12, 14 of the ring 10 serves not only as a means for wiping the brush as above described, but it also serves as a support for the central portion of the closure member 8 when the can is opened by cutting said closure member immediately inside the bead 7, thereby preventing the cut-out portion of the closure from dropping into the can.

In Figs. 5 and 6 there is shown a different embodiment of the invention in which the clamping and sealing ring is not provided with the brush-wiping section as in Figs. 1-4.

In the structure shown in Figs. 5 and 6 the can body 1, the collar 2 deformed to present the groove 4, the vertical wall 5 and bead 7, and the closure member 8 having the skirt 9 are the same as in Figs. 1-4.

In this embodiment, however, the clamping and sealing ring 11a is a single section ring which serves merely to clamp the skirt 9 of the closure member 8 tightly against the vertical wall 5 and also to reinforce said wall 5. This embodiment may be used where the brush-wiping feature is not necessary.

In both embodiments of the invention the clamping and sealing ring 10 or 11a functions also as a reinforcing ring for reinforcing the collar.

When the can is to be filled and sealed, the collar 2, the closure member 8, and the sealing ring are first assembled with the sealing ring tightly clamping and sealing the skirt 9 of the closure member against the vertical wall 5, and after the can has been filled then the assembled collar, closure member and sealing ring are placed in position, and the peripheral edge of the collar is

sealed to the top edge of the can body by the lock seam 3.

I claim:

A can for a brushable liquid comprising a can body, a closure-receiving collar situated within the top end of the can body, the peripheral edge portion of said collar being secured to the top edge of the can body with a lock seam, said collar having an annular horizontal portion extending inwardly from the wall of the can body, said horizontal portion merging into the upper edge of the outer wall of an annular depending U-shaped portion of the collar located below said horizontal portion, the upper edge of said inner wall being rolled inwardly to form an annular bead, a closure member of thin easily cut metal having a depending peripheral skirt section resting against and fitting within said inner vertical wall of the U-shaped portion of the collar, and a clamping member within said skirt having an outer ring section for clamping the skirt to said vertical wall and an inner ring section spaced from said outer ring section and defining the dispensing opening of the can, the top edge of said inner ring section constituting a brush-wiping edge, said inner ring section and said outer ring section connected at their lower edges by spaced bridges whereby excess paint wiped from the brush may drain back into said can.

HARRY SEBELL.
